COVERED RACK FOR DOORS

Harry Derman, Laurelton, Long Island, N. Y.

Application October 19, 1934, Serial No. 749,031

5 Claims. (Cl. 312—4)

This invention relates to covered racks designed for use in connection with doors of closets to utilize the space on the inner surface of the door for supporting such apparel as shoes, hats and neckties; and the object of the invention is to provide a rack of the class described comprising a rectangular frame in connection with which a plurality of hat, shoe or necktie supporting members are pivotally mounted to permit the swinging of said members from a normal position within the boundaries of the frame to a position extending from one side thereof; a further object being to provide a frame of the class described preferably composed of two similar frame parts bolted or otherwise coupled together when set up for use, whereby the complete frame may be shipped in a relatively small compact package when in its collapsed state; a further object being to provide an enclosure for the rack or the supporting members thereof preferably in the form of a curtain supported on a rod arranged at the upper end portion of the frame, the rod being so arranged as to support the curtain outwardly of said supporting members; a further object being to provide a top or cover arranged over the frame parts to protect and cover the same; and with these and other objects in view, the invention consists in a rack of the class and for the purpose specified, which is simple and economical in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view indicating one of my improved racks completely set up for use upon the inner surface of a door.

Fig. 2 is a vertical sectional view of the structure shown in Fig. 1 with part of the construction broken away.

Fig. 3 is a perspective view showing the several parts of the rack in extended position and omitting the curtain and with parts broken away; and,

Fig. 4 is a side edge view of the two frame parts of the rack in collapsed position illustrating the compact packing of said frame parts.

In carrying my invention into effect, I provide an elongated frame 10 preferably consisting of separate rectangular frame parts 11 and 12, adjacent ends of which are secured together by winged nut bolts 13 or by other suitable means.

Pivottally supported within the frame part 11 are three similar supporting members 14, each consisting of side arms 15 joined at their outer end portions by cross bars 16. The bars 16 have spaced apertures in the upper edges thereof to receive dowel pins 17 having detachable button-shaped heads 18, said pins and heads forming hat supporting elements of conventional form. It will be understood that when the members 14 are swung into alignment with the side rails of the frame part 11, the pins 17 are removed to provide the compact packing of the separate frame parts.

The members 14 are supported in extended position by engagement of the side arms 15 thereof with blocks 19 secured to the inner surfaces of the side rails of the frame part 11 as may be seen upon a consideration of Fig. 2 of the drawing. Three of the members 14 are employed in connection with the frame part 11 and the lowermost member includes a necktie supporting rod 20 movably supported in connection with said member by short arms 21 pivoted to the inner surfaces of the side arms 15 of said member so that the arms 21 and rod 20 may be swung into alignment with the arms 15 of the lower member 14 as well as within the boundaries of the side rails of the frame part 11 to provide said compact folding of the complete device.

The frame part 12 is of the same dimensions as the frame part 11 and pivotally supported in connection with the lower end portion of said part is a plurality of supporting members 22, three of which are shown. Each of these members consists of side arms 23, joined by a plurality of cross bars 24, the latter seating in notches or recesses 23a formed in the upper surfaces of the arms 23. The members 22 when extended from the frame part 12 are arranged in a downwardly inclined direction and form shoe supporting members in connection with which a number of pairs of shoes may be supported, that is to say, two or more pairs on each of the members 22. The heels of the shoes 45 are disposed over the innermost cross bar 24a of each supporting member. The two uppermost members 22 are supported in their inclined position by blocks 25 secured to the inner surfaces of the side rails of the frame part 12, whereas the lowermost member 22 is supported in its inclined position by engagement with the bottom cross rail 12a of the frame part 12.

It will be understood that when the frame part 12 is in collapsed position, the members 22 are 55

swung upwardly and are contained within the boundaries of the side rails of said frame part so that when both frame parts are collapsed, they may be placed face to face for packing and shipment in the manner indicated in the side edge view in Fig. 4 of the drawing.

When the separate parts 11 and 12 of the frame 10 are secured together by the bolts 13, the same may be attached to the inner surface of a door indicated at 26 in Figs. 1 and 2 of the drawing by passing screws or other devices through the top rail 11a of the frame part 11 and the bottom rail 12a of the frame part 12. If additional securing is thought to be necessary, other securing devices may be passed through the side rails of said parts. However, the said top and bottom rails will be apertured for the first securing devices as is indicated in the top rail 11a in Fig. 3 of the drawing.

20 It will be understood that when the frame 10 or the separate parts 11 and 12 of the rack is attached to the door, the members 14—22 may be swung into extended position or into collapsed position at will, the only thing being that the hat supporting elements consisting of the pins 17 and heads 18 must be attached and detached.

The complete rack as described, by virtue of the simplicity of its construction, may be manufactured to sell at a very reasonable retail price, thus placing the article within reach of the public at large. By adding a slight expense to the complete rack, the appearance thereof, when in use, may be enhanced and greater efficiency and utility provided by including a covering. For 35 this purpose, I provide a wire frame 27 which is substantially yoke-shaped in form and the hook-shaped ends 27a thereof are detachably coupled with the upper end of the frame part 11 by springing said end portions of the frame 40 inwardly and then passing the same outwardly through apertures 11b formed in the side rails of the frame part and allowing the shank portions 27b to seat in recesses formed on the inner surfaces of said rails. This wire frame extends 45 beyond the sides of the frame part 11 and forwardly beyond the members 14—22 and provides a support for curtains 28, 28a which hang downwardly over the entire rack construction and conceal said rack from view as well as the articles 50 supported thereon. The curtains 28 and 28a join each other centrally as seen at 28b where they may be attached or coupled together if desired. When detached, these curtains may be swung to both sides of the frame to give access to the 55 articles of apparel supported thereon. The curtain supporting frame 27 extends above the top of the frame part 11 so as to provide necessary clearance above the hats supported on the headed pins provided for this purpose.

60 I may also employ above the frame 27 a top plate 29 forming a cover for the top of the complete unit. This plate includes a downwardly extending back or inner flange 29a located rearwardly of the top cross rail 11a and secured in 65 position by the screws or other means employed for holding the frame part 11 in position. The side edges of the part 29 may also be flanged as indicated at 29b to aid in supporting the same and to give rigidity thereto. The part 29 may 70 be composed of sheet metal or of heavy fibre or cardboard depending entirely upon the price at which the complete article is to be sold.

By providing the top wall part 29 and the curtains 28, 28a, the articles of apparel supported 75 upon the rack may not only be concealed from

view when the door 26 is swung into open position, but at the same time protected from dust and dirt to a large degree. The mounting of the top wall 29 will be such as to permit free movement of the curtains 28, 28a upon the supporting rod. It is 5 also preferred that the upper edge of the curtains 28, 28a be provided with supporting rings or other mounting members 30 to provide free movement of the curtains on the rod of the frame 27.

It will be understood that my improved apparel 10 supporting rack may be mounted in connection with any type of a support and the several supporting members may have a different arrangement within the frame to adapt it to the intended uses. It is known in the art to provide shoe racks 15 for arrangement upon closet doors, and it is also known that garment hanging racks have been provided for the doors of closets, the latter including a shelf member, but to the best of my knowledge and belief, a combination rack serving 20 the three distinct and specific purposes herein named has never heretofore been known to the art, and especially wherein the rack is of collapsible construction providing the compact packing 25 of the same.

Having fully described my invention, what I claim as new and desire to secure by Letters Patent, is:

1. A rack for supporting shoes, hats and neckties, said rack comprising an elongated, rectangular frame adapted to be mounted upon the surface of a closet door to cover the major portion of the surface area thereof, the upper end portion of the frame having vertically spaced supporting members normally collapsible within the boundaries of 30 the frame, hat supporting pins detachably mounted on said members, the lower supporting member having means for supporting neckties in connection therewith, the other or lower end portion of the frame having vertically spaced shoe supporting members normally contained within the boundaries of the frame, said supporting members being extensible into angular positions with respect to the frame at the outer or exposed surface thereof, means within the boundaries of the 40 frame engaging the supporting members to support the same in the desired angular position with respect to said frame, and said frame serving to space the upper and lower supporting members in a fixed and widely spaced relationship with 45 respect to each other.

2. A rack for supporting shoes, hats and neckties, said rack comprising an elongated, rectangular frame adapted to be mounted upon the surface of a closet door to cover the major portion of the surface area thereof, the upper end portion of the frame having vertically spaced supporting members normally collapsible within the boundaries of the frame, hat supporting pins 55 detachably mounted on said members, the lower supporting member having means for supporting neckties in connection therewith, the other or lower end portion of the frame having vertically spaced shoe supporting members normally contained within the boundaries of the frame, said supporting members being extensible into angular positions with respect to the frame at the outer or exposed surface thereof, means within the boundaries of the frame engaging the supporting members to support the same in the desired angular position with respect to said frame, said frame serving to space the upper and lower supporting members in a fixed and widely spaced relationship with respect to each other, said frame being composed of two substantially similar 60

frame parts arranged one upon the other in edge to edge relation in forming said elongated frame, and means for coupling said frame parts together.

5. 3. A rack for supporting shoes, hats and neckties, said rack comprising an elongated, rectangular frame adapted to be mounted upon the surface of a closet door to cover the major portion of the surface area thereof, the upper end portion of the frame having vertically spaced supporting members normally collapsible within the boundaries of the frame, hat supporting pins detachably mounted on said members, the lower supporting member having means for supporting neckties in connection therewith, the other or lower end portion of the frame having vertically spaced shoe supporting members normally contained within the boundaries of the frame, said supporting members being extensible into angular positions with respect to the frame at the outer or exposed surface thereof, means within the boundaries of the frame engaging the supporting members to support the same in the desired angular position with respect to said frame, said frame serving to space the upper and lower supporting members in a fixed and widely spaced relationship with respect to each other, the frame including long side rails, each of said supporting members comprising side arms pivoted to the side rails of the frame, and a cross bar joining said side arms outwardly of the pivots of said arms, and said necktie supporting means comprising a rod mounted on short arms pivoted to and collapsible within the boundaries of the supporting member therefor.

35. 4. A rack for supporting shoes, hats and neckties, said rack comprising an elongated, rectangular frame adapted to be mounted upon the surface of a closet door to cover the major portion of the surface area thereof, the upper end portion of the frame having vertically spaced supporting members normally collapsible within the boundaries of the frame, hat supporting pins detachably mounted on said members, the lower supporting member having means for supporting neckties in connection therewith, the other or lower end portion of the frame having vertically spaced shoe supporting members normally contained within the boundaries of the frame, said supporting members being extensible into angular positions with respect to the frame at the outer or exposed surface thereof, means within

the boundaries of the frame engaging the supporting members to support the same in the desired angular position with respect to said frame, said frame serving to space the upper and lower supporting members in a fixed and widely spaced relationship with respect to each other, and means detachably coupled with the frame above the uppermost supporting member thereof for supporting an enclosure around the front and sides and throughout the length of the frame to cover hats, neckties and shoes arranged on the supporting means therefor.

5. 5. A rack for supporting shoes, hats and neckties, said rack comprising an elongated, rectangular frame adapted to be mounted upon the surface of a closet door to cover the major portion of the surface area thereof, the upper end portion of the frame having vertically spaced supporting members normally collapsible within the boundaries of the frame, hat supporting pins detachably mounted on said members, the lower supporting member having means for supporting neckties in connection therewith, the other or lower end portion of the frame having vertically spaced shoe supporting members normally contained within the boundaries of the frame, said supporting members being extensible into angular positions with respect to the frame at the outer or exposed surface thereof, means within the boundaries of the frame engaging the supporting members to support the same in the desired angular position with respect to said frame, said frame serving to space the upper and lower supporting members in a fixed and widely spaced relationship with respect to each other, means detachably coupled with the frame above the uppermost supporting member thereof for supporting an enclosure around the front and sides and throughout the length of the frame to cover hats, neckties and shoes arranged on the supporting means therefor, said means comprising a yoke-shaped member having inwardly directed hook ends detachable with respect to the upper end portion of the frame, and a top cover plate retained between the upper end of the frame and the door in connection with which the frame is mounted, said plate being substantially of the contour of and being disposed above said yoke-shaped member.

HARRY DERMAN. 50
